UNITED STATES PATENT OFFICE.

FRANCIS LINCOLN YOUNG, OF NEW YORK, AND RICHARD JAMES PRETTIE, OF JAMAICA,
NEW YORK, ASSIGNORS TO THE AEOLIAN COMPANY, A CORPORATION OF CON-
NECTICUT.

DISK-RECORD-FILING CABINET.

1,276,153.

Specification of Letters Patent. Patented Aug. 20, 1918.

Application filed July 31, 1915. Serial No. 42,943.

To all whom it may concern:

Be it known that we, FRANCIS LINCOLN YOUNG and RICHARD JAMES PRETTIE, citizens of the United States, residing, respectively, at New York city, in the county of New York, and Jamaica, in the county of Queens and State of New York, have invented certain new and useful Improvements in Disk-Record-Filing Cabinets, of which the following is a specification.

Our present invention is a disk-record filing cabinet, the features and advantages of which will be apparent to those skilled in the art from an understanding of the following description in connection with the drawings.

In these Figure 1 is a vertical section partly in elevation on the line 1—1 in Fig. 2 on a larger scale of a record cabinet embodying one of the forms that our invention may take, Fig. 2 is a partial front view of the same cabinet, and Fig. 3 is an enlarged sectional view of a detail.

Describing now the specific devices of the drawings:—1 is a box having an opening, through which the records are accessible, protected by the hinged door 2. 3 is a rod extending lengthwise of the box near the front and is supported above the bottom of the box by the standards 4. 5 and 6 are rubber or equivalently covered rods supported by said standards below and to either side of the rod 3.

7—7 are a plurality of elbow shaped hangers having headed projections 8 from their elbows whereon the records are adapted to be hung or supported by their center holes in face relation to both arms of the hangers. The heads of the projections 8 prevent the records from working off the projections. Compare Figs. 1, 2 and 3, the records being designated 9.

The ends of the hanger-arms extend beyond the periphery of the records, all the lower ends 10 being pivotally supported on the aforesaid rod 3, said ends projecting below said rod so as to be located between the rubber covered rods 5 and 6 against which they strike and by which they are stopped and supported in their inner and outer positions respectively (see Fig. 1). The purpose of the covering on the rods 5 and 6 is to deaden the noise of their contact with the hangers.

55 The opposite ends 11 of the hangers are

formed into finger pieces bearing designating index numbers for the records, said finger pieces serving to oscillate the hangers and records into and out of the cabinet.

Each hanger may have a third arm or 60 part 12 extending from the point of the elbow, so that each hanger has three record-contacting or supporting arms 120° apart. Rubber facings or bands 13 or equivalent protective material are provided on these 65 arms to prevent them from scratching the records.

When the hangers and records are in their inner position, they are contained wholly inside the cabinet so that the door 2 70 (Fig. 1) can be shut. In this position, the finger pieces 11 are presented toward the opening in the cabinet with the record-designations thereon plainly visible as in Fig. 2. Any of the records can be withdrawn by pulling its finger piece forwardly through the opening in the cabinet, in which position the hanger is supported by the stop-rod 6. The record has thus been brought forward edgewise out of the row, 80 and can be lifted off the projection 8 of its hanger and by the reverse procedure can be replaced on the hanger and returned into the cabinet.

Of course changes may be made in the 85 above which will nevertheless still be within the spirit and intent of our invention and we propose to cover any such by the annexed claims under the doctrine of equivalents.

90 What we claim is:—

1. A record-cabinet for center-holed disk records, having housed within it a plurality of hangers for supporting the records vertically in side-by-side relation, each hanger provided on one side face thereof with a lateral extension receivable through the hole in a record to support the record on the hanger; said hangers being mounted for movement outwardly of the cabinet to carry 100 the records into position to be grasped.

2. A record-cabinet for center-holed disk records, having housed within it a plurality of hangers for supporting the records vertically in side-by-side relation, each hanger provided on one side face thereof with a lateral extension receivable through the hole in a record to support the record on the hanger and having a terminal head to prevent accidental displacement of the record 110

from the extension; said hangers being mounted for movement outwardly of the cabinet to carry the records into position to be grasped.

- 5 3. A record-cabinet for center-holed disk records, having housed within it a plurality of hangers for supporting the records vertically in side-by-side relation, each hanger consisting of a plurality of arms radiating 10 from a common center and having on one of its side faces a lateral extension located substantially at said center and receivable through the hole in a record to support the record on the hanger; said hangers being 15 mounted for movement outwardly of the cabinet to carry the records into position to be grasped.

4. A record-cabinet for center-holed disk records, containing a plurality of movable 20 hangers which support said records vertically in side-by-side relation, each of said hangers having a lateral extension receivable through the hole in a record to support the record on the hanger, and each consisting 25 of an elbow shaped part pivoted at one end to the cabinet and having the aforesaid record-supporting extension at the angle of the hanger.

5. A record-cabinet for center-holed disk 30 records, containing a plurality of movable hangers which support said records vertically in side-by-side relation, each of said hangers having a lateral extension receivable through the hole in a record to support 35 the record on the hanger, and each consisting of an elbow shaped part pivoted at one end to the cabinet and having the aforesaid record-supporting extension at the angle of 40 the hanger and a part projecting from the point portion of the elbow to contact with the face of the record.

6. A record-cabinet for center-holed disk 45 records, containing a plurality of movable hangers which support said records vertically in side-by-side relation, each of said hangers having a lateral extension receivable through the hole in a record to support 50 the record on the hanger, and each consisting of an elbow shaped part pivoted at one end to the cabinet and having the aforesaid record-supporting extension at the angle of the hanger, the other end of said elbow

shaped hanger constituting a finger-piece by which to manipulate the hanger, each hanger having an extension beyond the edge 55 of the supported record by which it is pivotally connected to the cabinet, and stop means which engage said hangers to support them and the records in a row side by side as aforesaid in the cabinet and also to support them when severally pivoted edgewise out from the row when removing a record or records from the hangers.

7. A record cabinet for center-holed disk records comprising a box having an opening through which to remove and return the records, a plurality of elbow shaped hangers pivotally supported side by side in a row within said box so that each is independently pivotable edgewise into and out of said row and projections for the elbow of said hangers receivable into the holes of the records for supporting them on the hangers in face relationship with both arms thereof, both ends of the hangers extending beyond the periphery of the supported records, one set of said ends being the parts by which the hangers are pivotally supported in the box, and the other ends of the same hangers being finger pieces by which 80 to manipulate the hangers.

8. A record-cabinet for center-holed disk records, containing a plurality of movable hangers which support said records vertically in side-by-side relation, each of said hangers consisting of an elongated member having a lateral extension from its upper end receivable through the hole in the record to support the record on the hanger, each hanger member projecting beyond the edge of the supported record and being there 90 pivotally connected to the cabinet; and stop means which engages said projecting portion of the hangers and supports them and the records in a row side-by-side as aforesaid in the cabinet and also supports them when severally pivoted edgewise out from the row when removing a record or records from the hangers.

In testimony whereof, we have signed our names to this specification this 28th day of July, 1915.

FRANCIS LINCOLN YOUNG,
RICHARD JAMES PRETTIE.
